TELESCOPIC TOWEL RACK OR SIMILAR
ARTICLE

John A. Woodworth, Los Angeles, Calif.

Application June 19, 1950, Serial No. 10,617

Term of patent 14 years

(Cl. D4—3)

To all whom it may concern:

Be it known that I, John A. Woodworth, a citizen of the United States residing at Los Angeles, in the county of Los Angeles and State of California, have invented a new, original, and ornamental Design for Telescopic Towel Rack or Similar Article, of which the following is a specification, reference being had to the accompanying drawing, forming part thereof.

Figure 1 is a perspective view of a telescopic towel rack in its extended, or operative arrangement, showing my new design.

Figure 2 is a perspective view of the towel rack of Figure 1, but in its collapsed arrangement.

Figure 3 is a view in side elevation of the towel rack arranged as in Figure 2.

I claim:

The ornamental design for a telescopic towel rack or similar article, substantially as shown.

JOHN A. WOODWORTH.
